CLAIM

The ornamental design for a flotational diffuser, as shown and described.

DESCRIPTION

FIG. 1 is a top perspective view of a flotational diffuser, showing my new design;

FIG. 2 is a bottom perspective view thereof;

FIG. 3 is a top plan view thereof;

FIG. 4 is a bottom plan view thereof;

FIG. 5 is a front view thereof; and,

FIG. 6 is a top perspective view thereof, showing the lid of the diffuser removed therefrom.

The broken lines in the figures illustrate portions of the flotational diffuser that form no part of the claimed design.
